US00D938535S

(12) **United States Design Patent** (10) Patent No.: **US D938,535 S**
(45) Date of Patent: **** Dec. 14, 2021**

(54) **GOLF CLUB HEAD**

- (71) Applicant: **PARSONS XTREME GOLF, LLC**,
Scottsdale, AZ (US)
- (72) Inventors: **Robert R. Parsons**, Scottsdale, AZ
(US); **Michael R. Nicolette**, Scottsdale,
AZ (US); **Bradley D. Schweigert**, Cave
Creek, AZ (US); **Caleb S. Kroloff**,
Phoenix, AZ (US)
- (73) Assignee: **Parsons Xtreme Golf, LLC**,
Scottsdale, AZ (US)
- (**) Term: **15 Years**
- (21) Appl. No.: **29/796,673**
- (22) Filed: **Jun. 25, 2021**

Related U.S. Application Data

- (60) Division of application No. 29/772,038, filed on Feb.
26, 2021, now Pat. No. Des. 926,901, which is a
continuation-in-part of application No. 29/756,756,
filed on Oct. 30, 2020, and a continuation-in-part of
application No. 29/724,586, filed on Feb. 18, 2020,
which is a continuation-in-part of application No.
29/719,608, filed on Jan. 6, 2020, and a
continuation-in-part of application No. 29/717,441,
filed on Dec. 17, 2019, now abandoned, and a
continuation-in-part of application No. 29/717,071,
filed on Dec. 13, 2019, now abandoned.

CLAIM

The ornamental design for a golf club head, as shown and
described.

DESCRIPTION

FIG. 1 is a top perspective view of a golf club head;
FIG. 2 is a bottom perspective view of the golf club head of
FIG. 1;
FIG. 3 is a front elevational view of the golf club head of
FIG. 1;
FIG. 4 is a rear elevational view of the golf club head of FIG.
1;
FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1.
The broken lines shown on the drawings form no part of the
claimed design.
